UNITED STATES PATENT OFFICE

2,618,429

SHIPPING CONTAINER

John S. Donnell, Sarasota, Fla., assignor to
 Florida Fibre Box Company, Sarasota, Fla., a
 corporation of Florida

Application September 7, 1950, Serial No. 183,565

6 Claims. (Cl. 229—45)

1

The present invention relates generally to containers. More particularly, the invention relates to that type of container which is designed as an instrument or a medium for use in shipping fruit, vegetables or other articles, is formed of comparatively stiff material, such, for example, as double faced corrugated board, and as its parts or components comprises a rectangular open top box-like body and a complementary cover which is adapted when in place to close the open top of the body, and consists of a rectangular top and depending ends and sides.

One object of the invention is to provide a shipping container of this type which is an improvement upon and has certain inherent advantages over previously designed containers of the same general construction, and is characterized by the fact that it embodies a novel and effective releasable locking arrangement for securing the cover in its closed position with respect to the rectangular open top box-like body.

Another object of the invention is to provide a shipping container of the type under consideration in which the releasable locking arrangement for securing the cover in its closed position is in the form of two bendable locking tongues which are formed as integral parts of the central portions of the ends of the body, and are adapted to be inserted or threaded through adjacent slots in the top and ends of the cover.

Another object of the invention is to provide a shipping container of the last mentioned type and character in which the central portions of the end margins of the top of the cover have longitudinally extending slots for receiving the locking tongues when the cover is mounted in its closed position on the body, and the ends of the cover consist of spaced apart outer and inner walls and have formed in the central portions of their outer walls longitudinally extending slots into which the tongues may be inserted after being bent outwards and downwards around the portions of the outer walls of the cover ends that are above the last mentioned slots.

A further object of the invention is to provide a shipping container of the aforementioned character in which the central portions of the locking tongues are provided with U-shaped cuts to form ears which are adapted when the tongues are in their locked position, wherein they extend downwards through the longitudinally extending slots in the central portions of the outer walls of the ends of the cover to be bent inwards into underlying and interlocked relation with the parts of the outer walls that define the top portions of said slots.

A still further object of the invention is to provide a shipping container which is generally of new and improved construction, and is so designed that the releasable locking arrangement

2

for securing the cover in its closed or operative position does not add to or increase the cost of the container as a whole.

Other objects of the invention and the various advantages and characteristics of the present shipping container will be apparent from the following detailed description.

The invention consists in the several novel features which are hereinafter set forth and are more particularly defined by the claims at the conclusion hereof.

In the drawings which accompany and form a part of this specification or disclosure and in which like numerals of reference denote corresponding parts of the several views:

Figure 1 is a top perspective showing a shipping container embodying the invention with the locking tongues thereof in their locked position wherein they serve securely but releasably to hold the cover of the container in its closed position;

Figure 2 is a top perspective of the rectangular open top box-like body of the container, illustrating in detail the manner in which the ear equipped locking tongues are formed as integral parts of the central portions of the ends of the body;

Figure 3 is a vertical longitudinal section of the cover of the container showing the construction of the cover ends and illustrating the location of the slots for receiving the locking tongues;

Figure 4 is a vertical longitudinal section of the body of the container;

Figure 5 is a vertical longitudinal section showing the cover in its closed position and releasably secured in place by the locking tongues, and illustrating in detail the manner in which the ears on the central portions of the tongues so interlock with the portions of the outer walls of the cover ends that define the top parts of the longitudinal tongue receiving slots in the central portions of the outer walls of the cover ends securely but releasably to hold the tongues in place;

Figure 6 is a fragmentary vertical section on the line 6—6 of Figure 1; and

Figure 7 is a fragmentary end elevation of the container with certain parts removed and other parts shown in section for purposes of illustration.

The container which is shown in the drawings constitutes the preferred form or embodiment of the invention. It is primarily designed for use in shipping different articles such, for example, as fruit and vegetables and consists of a rectangular open top box-like body 10 and a complementary cover 11 for closing the open top of the body. The body and cover are preferably formed of comparatively stiff double faced corrugated board in order that the container as a whole possesses the desired and necessary rigidity and strength.

The container is illustrated as being of materially less height than the width or length although it is to be understood that if desired the container may be of any height. The two components constituting the container are formed of one piece blanks in order that the container is capable of being produced at a low cost.

The body 10 consists of a flat rectangular bottom 12, a pair of upstanding sides 13, and a pair of upstanding ends 14. The sides and ends of the body extend upwards at right angles to the bottom 12 and define with the latter an open top article retaining compartment. The sides 13 of the body 10 are of uniform height from end to end and consist of outer walls 15 and inner walls 16. The bottom margins of the outer walls 15 are formed integrally with the side margins of the bottom 12 and are connected thereto by right angle folds or bends 17. The inner walls 16 of the sides of the body are the same in shape as the outer walls 15 and have the top margins thereof joined to the top margins of the outer walls by inverted U-shaped folds 18. The end margins of the inner walls 16 are provided with integral flaps 19, and these extend inwards from and at right angles to said inner walls. Aligned holes 20 are formed in the outer and inner walls 15 and 16 in order to permit air to enter article retaining compartment for ventilating purposes. The ends 14 of the body 10 are the same in height as the sides 13 and consist of outer walls 21 and inner walls 22. The bottom margins of the outer walls 21 are formed integrally with the end margins of the bottom 12 and are connected thereto by right angle folds or bends 23. The end margins of the outer walls 21 are provided with integral inwardly extending right angle flaps 24 which fit between the end portions of the outer and inner walls of the sides 13 of the body. The inner walls 22 are the same in size as the outer walls 21 and have the top margins thereof joined to the top margins of said outer walls by inverted U-shaped folds 24. The bottom margins of the inner walls 22 are provided with integral downwardly extending tongues 25. These, as best shown in Figures 2, 6 and 7 of the drawings, fit within slots 26 in the end margins of the body bottom 12. The flaps 19 on the end margins of the inner walls 16 of the sides 13 fit between the end portions of the outer and inner walls 21 and 22 of the ends 14 of the body. The central portions of the inner walls 22 of the body ends are die cut between their bottom and top edges in order to form locking tongues 27. The latter, as described more in detail hereinafter, serve releasably to secure the cover 11 in its closed position wherein it covers the top of the article retaining compartment that is formed by the bottom, sides and ends of the body. Certain ends of the locking tongues 27 are attached to the central portions of the top margins of the outer walls 21 by hinge connections 28 in order that the tongues may be swung upwards in a coplanar relation with the outer walls 21 when the cover is mounted in place on the body, and it is desired to use the tongues releasably to secure the cover in place. Preferably the locking tongues are tapered in the direction of their free ends. The tongues are sufficiently flexible so that they may be bent outwards and downwards into their hereinafter described locked position. The central portions of the locking tongues are provided with U-shaped slits 29 and these form or define hinged ears 30. When the locking tongues are bent outwards and downwards into their locked position the hinge connections

between the ears 30 and the central portions of the tongues are located at the bottoms of the ears and permit the ears to be bent or swung inwards.

5 In assembling the body 10 of the container outer walls 15 of the sides 13 are swung upwards with respect to the bottom 12 while the inner walls 16 are in substantially coplanar relation therewith. Thereafter the outer walls 21 of the ends of the body are swung upwards with respect to the body bottom while the inner walls 22 are in substantially coplanar relation therewith. After these steps the flaps 19 and the end margins of the outer walls 21 are swung or manipulated into lapped relation with the inner surfaces of the end portions of the outer walls 15. Thereafter the inner walls 16 of the body sides are swung inwards and downwards and the flaps 19 on their end margins are swung outwards into lapped relation with the inner surfaces of the end portions of the outer walls 29. At the conclusion of this step or operation the inner walls 22 are swung inwards and downwards. During such swinging of the inner walls 22 the depending tongues 25 move in interlocked relation with the slots 26 in the end margins of the body bottom 12. After assembly of the body the locking tongues 27 are swung upwards as shown in Figure 2.

The cover 11 of the container is shaped to fit over the upper margins of the sides and ends of the body and consist of a flat rectangular top 31, a pair of depending sides 32 and a pair of depending ends 33. The top 31 is shaped conformably to but is slightly larger than the bottom 12 of the body 10. The sides 32 of the cover 11 are of single thickness and have the top margins thereof connected to the side margins of the top by right angle folds or bends 33. The end margins of the cover sides 32 are provided with integral inwardly extending right angle flaps 34. The ends 33 of the cover are substantially the same in height as the sides 32 and consist of outer walls 35 and inner walls 36 in spaced relation with the said outer walls. The outer walls 35 have the top margins thereof connected to the end margins 31 by right angle folds or bends 35a. The inner walls 36 of the cover ends have the bottom margins thereof joined to the bottom margins of the outer walls 35 by U-shaped folds 37. The top margins of the inner walls 36 are provided with integral upstanding tongues 38. These fit within slots 39 in the end marginal portions of the cover top 31. In assembling the cover 11 the sides 32 are first bent at right angles to the top 31. Thereafter the outer walls 35 with the inner walls 36 in coplanar relation therewith are bent at right angles to the cover top. After this operation the flaps 34 are swung into abutting relation with the inner surfaces of the end portions of the outer walls 35. Thereafter the inner walls 36 are swung inwards in the direction of the cover top until the tongues 38 move into interlocked relation with the slots 39.

65 The central portions of the end margins of the top 31 of the cover 11 are provided with longitudinally extending tongue receiving slots 40. When the cover 11 is shifted downwards into its closed position with respect to the body 10, the locking tongues 27 slide upwards through the slots 40 (see dotted lines in Figure 1). The central portions of the outer walls 35 of the ends of the cover are provided with longitudinally extending tongue receiving slots 41 and the central portions of the U-shaped folds 37 are provided

with longitudinally extending tongue receiving slots 42. The last mentioned slots, that is, the slots 41 and 42, are preferably the same in length as the slots 40. As best shown in Figures 1 and 5, the locking tongues 27 after insertion through the slots 40 in connection with mounting of the cover 11 on the body 10 are adapted to be swung or bent outwards and then downwards. After such bending of the locking tongues the free ends are inserted into the slots 41 in the central portions of the outer walls 35, are then slit or pulled downwards so they extend through the slots 42 as shown in full lines in Figure 1. When the locking tongues 27 are in their locked or operative position as heretofore described, the inner end portions extend around the portions of the outer walls 35 that are directly above the slots 41, the central portions underlie the portions of the end walls 35 that are directly beneath the slots 41, and the free outer end portions extend downwards through the slots 42. Because of the inner woven arrangement of the locking tongues with respect to the slots 41 and 42, the tongues when in their operative position serve effectively to hold the cover 11 in its closed position. The ears 30 on the central portions of the locking tongues are adapted when the tongues are in their locked position to be bent inwards so that the upper edge portions thereof underlie the portions of the outer walls 35 that define the top edges of the slots 41. When the ears 30 are in place the locking tongues 27 are positively secured in their locked position. When it is desired to remove the cover 11 the ears 30 are swung outwards so as to disengage them from the portions of the outer walls 35 to define the top edges of the slots 41. Thereafter the tongues are pulled or slipped upwards so as to remove them from the slots 42 and 41. As soon as the locking tongues are swung upwards after being removed from the slots 42 and 41 the cover may be removed from the body by sliding it upwards relatively thereto.

The herein described shipping container effectively and efficiently fulfills its intended purpose by reason of the fact that it includes the ear equipped locking tongues 27 which when in their operative or locked position serve securely to hold the cover of the container in its closed position on the rectangular box-like body 10. By reason of the fact that the locking tongues are formed as integral parts of the ends of the body they do not increase the cost of producing the container as a whole.

The invention is not to be understood as restricted to the details set forth since these may be modified within the scope of the appended claims without departing from the spirit and scope of the invention.

Having thus described the invention, what I claim as new and desire to secure by Letters Patent of the United States is:

1. As a new article of manufacture, a shipping container comprising an open top box-like body formed of comparatively stiff material and embodying a rectangular bottom, a pair of opposed sides connected to, and extending upwards from, the side margins of the bottom and a pair of opposed ends connected to, and extending upwards from the end margins of the bottom and provided on the top margins thereof with normally upstanding laterally bendable locking tongues, and a complemental cover formed of comparatively stiff material, embodying a rectangular top, a

pair of opposed sides connected to, and depending from, the side margins of the top and a pair of opposed ends, connected to and depending from, the end margins of the top and in the form of spaced apart outer and inner walls, and having tongue receiving slots formed in the end margins of its top and tongue receiving slots formed in the outer walls of its ends substantially midway between the upper and lower edges of said outer walls, said tongues being adapted when the cover is shifted downwards into its closed position with respect to the body to pass substantially completely through the first mentioned slots and being further adapted after passing through said first mentioned slots to be bent outwards and downwards and then inserted inwards and downwards through the second mentioned slots in order to assume a cover locking position wherein portions thereof fit between the portions of said outer and inner walls that are beneath said second mentioned slots.

2. As a new article of manufacture, a shipping container comprising an open top box-like body formed of comparatively stiff material and embodying a rectangular bottom, a pair of opposed sides connected to, and extending upwards from, the side margins of the bottom and a pair of opposed ends connected to, and extending upwards from, the end margins of the bottom and provided on the top margins thereof with integral normally upstanding laterally bendable locking tongues, and a complemental cover formed of a one piece blank of comparatively stiff material, embodying a rectangular top, a pair of opposed sides connected to, and depending from, the side margins of the top and a pair of opposed ends connected to and depending from the end margins of the top and consisting of spaced apart outer and inner walls with the bottom margins thereof joined together by U-shaped folds, and having tongue receiving slots formed in the end margins of its top, tongue receiving slots formed in the outer walls of its ends substantially midway between the upper and lower edges of said outer walls and tongue receiving slots formed in the U-shaped folds of the ends thereof, said tongues being adapted when the cover is shifted downwards into its closed position with respect to the body to pass substantially completely through the first mentioned slots and being further adapted after passing through said first mentioned slots to be bent outwards and downwards and then inserted inwards through the second mentioned slots and downwards through the third mentioned slots in order to assume a cover locking position wherein portions thereof fit between the portions of said outer and inner walls that are between said second and third mentioned slots.

3. As a new article of manufacture, a shipping container comprising an open top box-like body formed of comparatively stiff material and embodying a rectangular bottom, a pair of opposed sides connected to, and extending upwards from, the side margins of the bottom and a pair of opposed ends connected to, and extending upwards from, the end margins of the bottom and provided on the top margins thereof with integral normally upstanding laterally bendable locking tongues, and a complemental cover formed of a one piece blank of comparatively stiff material, embodying a rectangular top, a pair of opposed sides connected to, and depending from, the side margins of the top and a pair of opposed ends connected to and depending from the end mar-

gins of the top and consisting of spaced apart outer and inner walls with the bottom margins thereof joined together by U-shaped folds, and having tongue receiving slots formed in the end margins of its top, tongue receiving slots formed in the outer walls of its ends substantially midway between the upper and lower edges of said outer walls and tongue receiving slots formed in the U-shaped folds of the ends thereof, said tongues being adapted when the cover is shifted downwards into its closed position with respect to the body to pass substantially completely through the first mentioned slots and being further adapted after passing through said first mentioned slots to be bent outwards and downwards and then inserted inwards through the second mentioned slots and downwards through the third mentioned slots in order to assume a cover locking position wherein portions thereof fit between the portions of said outer and inner walls that are between said second and third mentioned slots, the central portions of the locking tongues being cut and shaped to form integral laterally bendable ears which are adapted when the tongues are in their cover locking position to be bent inwards into a position wherein they are interlocked with the portions of the outer walls of the cover ends directly over the second mentioned slots and serve releasably to retain the tongues in their said cover locking position.

4. As a new article of manufacture, a shipping container comprising an open top box-like body formed of comparatively stiff material and embodying a rectangular bottom, a pair of opposed sides connected to, and extending upwards from the side margins of the bottom and a pair of opposed ends connected to, and extending upwards from, the end margins of the bottom consisting of outer and inner walls with the top margins thereof joined together by inverted U-shaped folds and having portions of their inner walls cut downwards from their upper edges to form elongated locking tongues which are joined to the upper margins of the other walls by the adjacent portions of the inverted U-shaped folds and are hence capable of being swung laterally, and a complemental cover formed of comparatively stiff material embodying a rectangular top, a pair of opposed sides connected to, and depending from, the side margins of the top and a pair of opposed ends connected to, and depending from, the end margins of the top and in the form of spaced apart outer and inner walls, and having tongue receiving slots formed in the end margins of its top and tongue receiving slots formed in the outer walls of its ends substantially midway between the upper and lower edges of the last mentioned outer walls, said tongues being adapted when they are swung upward into a vertical position and the cover is shifted downwards into its closed position with respect to the body to pass substantially completely through the first mentioned slots and being further adapted after passing through said first mentioned slots to be bent outwards and downwards and then inserted inwards and downwards through the secord mentioned slots in order to assume a cover locking position wherein portions thereof fit between the portions of the outer and inner walls of the cover ends that are beneath said second mentioned slots.

5. As a new article of manufacture, a shipping container comprising an open top box-like body formed of a one piece blank of double faced corrugated board and embodying a rectangular bot-

tom, a pair of opposed sides connected to, and extending upwards from, the side margins of the bottom and a pair of opposed ends connected to, and extending upwards from, the end margins of the bottom, consisting of outer and inner walls with the top margins thereof joined together by inverted U-shaped folds and having the central portions of their inner walls cut downwards from their upper edges to form elongated locking tongues which are joined to the central portions of the upper margins of the outer walls by the central portions of the inverted U-shaped folds and are hence capable of being swung laterally, and a complemental cover formed of a one piece blank of double faced corrugated board, embodying a rectangular top, a pair of opposed sides connected to, and depending from, the side margins of the top and a pair of opposed ends connected to, and depending from, the end margins of the top and consisting of spaced apart outer and inner walls with the bottom margins thereof joined together by U-shaped folds, and having tongue receiving slots formed in the central portions of the end margins of said top, tongue receiving slots formed in the central portions of the outer walls of its ends at points substantially midway between the upper and lower edges of the last mentioned outer walls and tongue receiving slots formed in the central portions of the U-shaped folds of the ends thereof, said tongues being adapted when they are swung upwards into a vertical position and the cover is shifted downwards into its closed position with respect to the body to pass substantially completely through the first mentioned slots and being further adapted after passing through said first mentioned slots to be bent outwards and downwards and then inserted inwards through the second mentioned slots and downwards through the third mentioned slots in order to assume a cover locking position wherein portions thereof fit between the portions of the outer and inner walls of the cover ends that are between said second and third mentioned slots.

6. As a new article of manufacture, a shipping container comprising an open top box-like body formed of comparatively stiff material and embodying a rectangular bottom, a pair of opposed sides connected to, and extending upwards from, the side margins of the bottom and a pair of opposed ends connected to, and extending upwards from, the end margins of the bottom, consisting of outer and inner walls with the top margins thereof joined together by inverted U-shaped folds and having the portions of their inner walls cut downwards from their upper edges to form elongated locking tongues which are joined to the upper margins of the outer walls by the adjacent portions of the inverted U-shaped folds and are hence capable of being swung laterally, and a complemental cover formed of comparatively stiff material, embodying a rectangular top, a pair of opposed sides connected to, and depending from, the side margins of the top and a pair of opposed ends connected to, and depending from, the end margins of the top and consisting of spaced apart outer and inner walls with the bottom margins thereof joined together by U-shaped folds, and having tongue receiving slots formed in the end margins of its top, tongue receiving slots formed in the outer walls of its ends substantially midway between the upper and lower edges of the last mentioned outer walls and tongue receiving slots formed in the U-shaped folds of the ends thereof, said tongues being

adapted when they are swung upwards into a vertical position and the cover is shifted downwards into its closed position with respect to the body to pass substantially completely through the first mentioned slots and being further adapted after passing through said first mentioned slots to be bent outwards and downwards and then inserted inwards through the second mentioned slots and downwards through the third mentioned slots in order to assume a cover locking position wherein portions thereof fit between the portions of the outer and inner walls of the cover ends that are between said second and third mentioned slots, the central portions of the locking tongues being cut and shaped to form integral laterally 15 bendable ears which are adapted when the tongues are in their cover locking position to be

bent inwards into a position wherein they are interlocked with the portions of the outer walls of the cover ends that are directly above the second mentioned slots and serve releasably to retain the tongues in their said cover locking position.

JOHN S. DONNELL.
